UNITED STATES PATENT OFFICE

123,858

DESIGN FOR A GLASS TUMBLER OR ARTICLE OF SIMILAR NATURE

Albert J. Dreitzer, New York, N. Y., assignor to Pitman-Dreitzer & Company, Inc., New York,
N. Y., a corporation of New York

Application October 3, 1940, Serial No. 95,622

Term of patent 7 years

To all whom it may concern:

Be it known that I, Albert J. Dreitzer, a citizen of the United States of America and a resident of New York, in the county of New York and State of New York, have invented a new, original, and ornamental Design for a Glass Tumbler
or Article of Similar Nature, of which the following is the specification, reference being had to the accompanying drawing, forming a part thereof.

Figure 1 is a perspective view of a glass tumbler
or article of similar nature, showing my new design.

Figure 2 is a side elevational view, partly in section.

I claim:

The ornamental design for a glass tumbler or article of similar nature, substantially as shown.
